SIGN

David N. Estes, Carlsbad, N. Mex.

Application June 13, 1938, Serial No. 213,493

9 Claims. (Cl. 40—130)

This invention appertains to new and useful improvements in signs, the present application being an improvement on my co-pending allowed application Serial No. 163,467, filed September 5, 1937.

The principal object of the present invention is to provide a sign of the luminous electrical discharge tube type which has associated therewith a character or background structure of insulation against which the tube engages, to the end that the illumination from the tube will be immediately reflected by an immediate portion of the background.

Another important object is to provide a sign wherein a background panel of colored glass is employed affording a permanent coloring effect, and eliminating the costly and tedious process of painting and otherwise preparing the background and the characters of present day signs, thus permitting a more attractive sign to be constructed at a much less cost from the standpoint of labor and material.

Another object is to provide a sign employing a background panel of insulation, to the end, that danger of short-circuiting and the like occasioned by the use of metallic panels are totally eliminated.

Another important object of the invention is to provide a sign of the character stated, which by having the luminous tubes disposed flatly against the panel of insulation, the usual large insulator tubes found in the conventional neon tube sign constructions are eliminated.

Still another important object of the invention is to provide a sign of the luminous electrical discharge tube construction wherein a background of preferably colored opaque glass is provided and sandblasted to form characters around which or over which the luminous tubes are disposed so that light from the tubes is immediately reflected from the roughened sandblasted surfaces affording a scintillating or twinkling effect not found in present types of electrical discharge tube sign displays.

Still another important object of the invention is to provide a construction in the manner immediately above stated wherein outlining tubes and centrally disposed tubes of different colors can be employed in conjunction with the sandblasted character for causing a merging effect of the colors on the sandblasted surface of the panel.

Still another important object of the invention is to provide a sign which because of the contrasting relation of the luminous discharge tubes

against the character will afford a sign which is equally appreciable during daytime when not illuminated as at night when the same is illuminated.

These and various other important objects and advantages of the invention will become apparent to the reader of the following specification.

In the drawings:

Figure 1 represents a front elevational view of a sign constructed in accordance with the present invention.

Figure 2 is a sectional view on the line 2—2 of Figure 1.

Figure 3 is a sectional view on the line 3—3 of Figure 1.

Figure 4 is a sectional view on the line 4—4 of Figure 1.

Figure 5 is a fragmentary enlarged elevational view of one of the tubes in association with one of the characters.

Figure 6 is a fragmentary front elevational view showing the tube employed to outline a character.

Figure 7 is a cross sectional view taken substantially on the line 7—7 of Figure 6.

Figure 8 is a fragmentary front elevational view of another arrangement of tubes.

Figure 9 is a fragmentary front elevational view of still another arrangement of tubes.

Figure 10 is a fragmentary front elevational view showing an arrangement of tubes without the sandblasted character.

Figure 11 is a sectional view taken substantially on the line 11—11 of Figure 10.

Figure 12 is a sectional view taken substantially on the line 12—12 of Figure 10.

Figure 13 is a vertical sectional view through a conventional neon sign.

Referring to the drawings wherein like numerals designate like parts, it can be seen in the drawings that numeral 5 represents the frame of any suitable metallic construction in which the panel 6 of insulation is mounted. It is desirable that the panel 6 be of colored glass and in most cases will be of black colored glass, but of course, can be of any desired colored glass.

In constructing these signs, the panel 6 is sandblasted to form the sign characters 7.

To distinguish from the characters shown in Figure 1 from the type of character shown in Figure 6 wherein the neon tube outlines the character, the sandblasted characters 7 are preferably cut substantially deep so that, as shown in Figure 3, an outlining shoulder 8 is defined.

against which the outer limits of light from the associated luminous tube 9 will reflect and beyond which reflection will be practically nil.

As shown in Figures 1 and 3, the luminous 5 electrical discharge tube 9 is disposed immediately against the character and runs longitudinally through the intermediate portion of the character, so that light emanating from the tube will be immediately reflected from the roughened 10 surface of the sandblasted character and by reason of the fact that the sandblasted characters on the front side of the panel have the tube mounted immediately against the same a scintillating or twinkling effect of the light reflecting from the minute ridges and protuberances of the sandblasted character will be highly appreciable.

As shown in Figure 4, these tubes 9 can be held by clips, each clip consisting of a threaded 20 member 10 disposed through an opening 11 in the panel 6, this threaded member 10 being split longitudinally from one end thereof and preferably being constructed of spring metal, with the thus formed bifurcations curved outwardly to 25 form spring clip arms 12 to snugly engage and retain the tube 9. A nut 13 can be engaged on the threaded portion of this clip structure to firmly hold the same in place on the panel.

While it is desirable that the sandblasted character 7 be cut substantially deep in the adaptation 30 of the invention illustrated in Figure 1 and also sectionally shown in Figure 3, it is not necessary to sandblast a character 14 as deeply. This character 14 is used in the adaptation of the invention 35 as illustrated in Figures 6, 7, 8 and 9 where the electrical discharge tube 15 outlines the entire character or a substantial portion of the character as illustrated in Figure 8.

As shown in Figure 6 the tube 15 outlines the 40 entire character and when some neutral colored background is used, light from the tube 15 will project inwardly on to the roughened surface of the sandblasting character 14 giving a scintillating or twinkling effect.

In the case of the form of letter shown in Figure 8 or in Figure 9 where a centrally disposed tube 16 is disposed across and preferably longitudinally of the character 14, it is desirable that the tube 16 be of a different colored glass than the 50 glass of the outlining tubes 15 so that the different colors will merge and blend into each other on the surface of the sandblasting character 14.

As is shown in Figure 12, the panel 6 is formed with very small openings 17 just barely large 55 enough to receive the backwardly bent end portions of the tubes 9, 15 or 16 and as can be seen in this view the tubes are snugly disposed immediately against the panel 6.

In some instances it may be desirable to eliminate entirely the sandblasted surface and provide a sign character constructed of the electrical discharge tube alone, but which because of the color of the glass of the tube the characters will be just as effective during daylight as at night- 60 time.

As shown in Figure 10, the panel 18 may be of some desirable color in contrast to the color of the tubes 19. The tube 19a is brought through the opening 18a and curved laterally to its upper- 70 most point and then extended straight downwardly as at b and then laterally as at c and upwardly again as at d to pass backwardly through the opening e. The second section of this letter G consists of the tube portion f which 75 comes through the opening g and is curved to the

point where it meets the vertical portion h where it extends downwardly to the laterally curved portion i and then extends upwardly as at k and then swings outwardly as at l in close spaced relation with the panel a to a point where it extends downwardly and upwardly as at m, the upper portion of the last-mentioned part being bent behind the horizontal portion n from where it extends downwardly and passes rearwardly through the opening p.

The foregoing types of signs obviously are a departure from the conventional type illustrated in Figure 13, wherein the panel 20 is usually of metal and has large openings therein through which the large insulating tubes 21 pass for 15 insulating the tail portion 22 of the electrical discharge tubes 23 from the metallic panel or background 20.

Furthermore these conventional types of signs 20 were employed on the background panel 20 to hold the tubes 23 at a substantial spaced position with respect to the background 20 so that the illumination from the tubes 23 have little illuminating effect on the characters painted on the background panel 20. As a matter of fact the 25 light from the tubes 23 instead of being concentrated on the particular characters, serve to illuminate the entire background and during the daytime the sign was nothing but a jumbled arrangement of tubes and unintelligible characters 30 painted on the background partly obscured by the tubes.

In constructing signs of the above design, it is desirable to have the background panel 6 and the luminous electrical discharge tubes of contrasting colors, to promote use of the sign in daytime, that is, when the tubes are not energized, besides affording a colorful display when illuminated for night use.

While the foregoing specification sets forth the 40 invention in specific terms, it is to be understood that numerous changes in the shape, size and materials may be resorted to without departing from the spirit and scope of the invention as claimed hereinafter.

Having described the invention, what is claimed as new is:

1. In a sign structure, a background panel of insulation, and a character formed luminous electric discharge tube disposed immediately against the front side of the said panel, and a character sandblasted from said panel adjacent said tube.

2. In a sign structure, a background panel of insulation, and a character formed luminous electric discharge tube disposed immediately against the front side of the said panel, said panel being formed with openings barely large enough for receiving the terminal portions of the tube.

3. In a sign structure, a background panel of insulation, and a character formed luminous electric discharge tube disposed immediately against the said panel, and a character sandblasted from said panel at the front side thereof adjacent said tube, said tube being disposed against the front side of the panel in character outlining position.

4. In a sign structure, a background panel of insulation, and a character formed luminous electric discharge tube disposed immediately against the said panel, and a character sandblasted from said panel adjacent said tube, said panel being sandblasted to a depth defining an outlining shoulder.

5. In a sign structure, a background panel of insulation, and a character formed luminous electric discharge tube disposed immediately against

the said panel, said panel being provided with an indented character having a depth defining and outlining shoulder, said tube being disposed on the panel and against the character at substantially the central portion thereof.

6. In a sign structure, a background panel of insulation, and a character formed luminous electric discharge tube disposed immediately against the said panel, said panel provided with a character having a roughened surface against which the said tube is disposed.

7. In a sign structure, a background panel of insulation, and a character formed luminous electric discharge tube disposed immediately against the said panel, said panel being provided with a character having a roughened surface against which the said tube is disposed, said character

being formed to define an outlining light projection limiting shoulder.

8. In a sign structure, a background panel, a character on the panel, the face of the character being roughened and being of light reflecting property, and a luminous electrical discharge tube disposed in front of the character and against the same.

9. In a sign structure, a background panel, a character on the panel at the front side thereof, the face of the character being roughened and being of light reflecting property, and a luminous electrical discharge tube disposed against the panel at the front side of the said character and adapted to project light immediately onto the roughened surface of the character.

DAVID N. ESTES.
